RACKET PRESS

Alexander Clowson, Gloversville, N. Y.

Application April 10, 1939, Serial No. 267,114

1 Claim. (Cl. 273—74)

The present invention relates to new and useful improvements in presses for different kinds or types of rackets and has for its primary object to provide, in a manner as hereinafter set forth, 5 a device of this character comprising a pair of hingedly connected, coacting jaws of a novel construction and arrangement which are adapted to firmly clamp a racket therebetween in a manner to prevent warping thereof.

10 Other objects of the invention are to provide a racket press of the aforementioned character which will be comparatively simple in construction, strong, durable, compact, light in weight and which may be manufactured at low cost.

15 All of the foregoing and still further objects and advantages of the invention will become apparent from a study of the following specification, taken in connection with the accompanying drawings wherein like characters of reference 20 designate corresponding parts throughout the several views, and wherein:

Figure 1 is a top plan view of a racket press constructed in accordance with the present invention.

25 Figure 2 is a view in side elevation thereof.

Figure 3 is a top plan view, showing the device open.

Figure 4 is an end elevational view.

Figure 5 is a detail view in vertical section, 30 taken substantially on the line 5—5 of Fig. 1.

Referring now to the drawings in detail, it will be seen that the embodiment of the invention which has been illustrated comprises a pair of 35 duplicate, complementary clamping jaws 1 and 2 of any suitable material. The jaws 1 and 2 are tapered in plan. It will also be observed that the jaws 1 and 2 are in the form of frames.

The jaws 1 and 2 are pivotally connected at 40 their small ends by a spring hinge 3. The construction and arrangement is such that the hingedly connected ends of the jaws 1 and 2 are spaced apart a distance equal to the thickness of the head of the racket therebetween, as at 4. Mounted on the pivoted end portion of the lower 45 jaw 1 is a block 5 constituting a stop for positively preventing contact of the racket with the hinge 3.

The reference numeral 6 designates a pair of angular hooks or latches which are hingedly 50 mounted, as at 7, on the free end portion of the lower jaw 1. As best seen in Fig. 5 of the drawing, the angular latches 6 are engageable over

the free end portion of the upper jaw 2. Ball detents 8 in the upper jaw 2 releasably secure the latches 6 thereto.

It is thought that the manner in which the device functions will be readily apparent from 5 a consideration of the foregoing. Briefly, the jaws 1 and 2 are swung to open position against the tension of the spring of the hinge 3 for the reception of the head of the racket therebetween. The jaw 2 is then swung to closed position on 10 the racket and firmly secured in closed position through the medium of the swinging latches 6. This is suggested in dotted lines in Fig. 1 of the drawings. Thus, the racket is firmly clamped between the jaws 1 and 2 and it will be subjected 15 to uniform pressure at all points. The press may be applied to or removed from the racket with a minimum of effort and in a comparatively short time and, when in use, occupies little space 20 as compared with presses now on the market. 20

It is believed that the many advantages of a racket press constructed in accordance with the present invention will be readily understood and although a preferred embodiment of the device 25 is as illustrated and described, it is to be understood that changes in the details of construction and in the combination and arrangement of parts 30 may be resorted to which will fall within the scope of the invention as claimed. 30

What is claimed is:

A press for the head of a tennis racket comprising a pair of duplicate elongated frames tapering toward one end, respectively, for clamping the racket head flat therebetween, a hinge connecting the shorter ends of said frames together for swinging movement of the frames into and from clamping relation, said hinge spacing said ends apart to accommodate said head therebetween and being spring tensioned to yieldingly retain the frames in clamping relation, and means to fasten the frames together in clamping relation comprising a pair of rightangled flat keepers swingably mounted on the longer end of one frame adjacent the opposite corners thereof for manipulation to hook the same over the corresponding end of the other frame into engagement therewith, and ball and socket devices on said keepers and said other end, respectively, for frictionally retaining said keepers in engaging position. 40 45 50

ALEXANDER CLOWSON.
